DESIGN FOR A DUPLICATING MACHINE

Norman B. Keller, Altadena, and Louis A. Keller, Los Angeles, Calif., assignors to Keller Manufacturing Corporation, a corporation of California

Application December 18, 1939, Serial No. 88,996

Term of patent 7 years

To all whom it may concern:

Be it known that we, Norman B. Keller and Louis A. Keller, citizens of the United States, residing, respectively, at Altadena, and Los Angeles, in the county of Los Angeles, State of California, have invented a new, original, and ornamental Design for Duplicating Machines, of which the following is a specification, reference being had to the accompanying drawing, forming part thereof.

In said drawing Figures 1 and 2 are perspective views looking at opposite sides of a duplicating machine showing our new design.

We claim:

The ornamental design for a duplicating machine, as shown.

NORMAN B. KELLER.
LOUIS A. KELLER.
